VEHICLE

Earnie W. Lucas, Wilson, N. C., assignor of forty-five per cent to Troy T. Barnes, A. C. Hinton, and R. M. Barnes, all of Wilson, N. C.

Application December 30, 1938, Serial No. 248,609

4 Claims. (Cl. 280—226)

This invention relates to a vehicle of the type adapted to be driven by power supplied to the wheels by manual efforts of the rider and more particularly it pertains to a child's toy vehicle which can be driven at relatively high speed with a minimum of effort.

Similar devices have been known for some time and have afforded a great deal of pleasure and exercise to children. Ordinarily the velocipedes, 10 scooters and the like known to the prior art are driven through levers, gear trains, chains and sprocket transmissions or the like by pedals operated by the feet of the occupant. Steering is ordinarily accomplished by handle bars or some 15 similar device manipulated by the hands. Vehicles of this type give exercise to the leg muscles and the muscles of the hips but the larger muscles of the abdomen and back are not called into play to any material extent.

20 Other toy vehicles are known which may be operated by a reciprocating lever adapted to be worked by the hands and it is also known to provide a driving means operated from a rocking platform. Vehicles of this type tend to bring most of the muscles of the body into operation 25 for driving but they are usually slow moving by reason of the fact that energy to supply locomotion is derived either from the relatively weak arm muscles or by the force of gravity acting by reason of a shift of the body of the occupant. 30 It is accordingly a primary object of my invention to provide an occupant-propelled vehicle which is capable of attaining a maximum speed with a minimum of effort thereby avoiding the above noted difficulties encountered in the prior 35 art.

It is a further object hereof to provide a foot-steered vehicle of the above type having an oscillating member upon which the rider sits, said oscillating means being so pivoted that advantage is 40 taken of the normal body pivot at the hips.

Still another object of my invention lies in the provision of an improved transmission gear capable of utilizing substantially all the energy supplied for locomotion.

45 Other objects and advantages of my invention will be apparent from the following detailed description of a preferred embodiment thereof when considered in connection with the attached drawing, wherein:

50 Figure 1 is a side elevation of the vehicle in partial section;

Figure 2 is a rear elevation of the vehicle illustrated in Figure 1;

55 Figure 3 is a partial section thereof on line 3—3 of Figure 2, illustrating the drive mechanism in detail; and

Figure 4 is a partial plan view of the forward end of the vehicle showing the mounting for the steering device.

Referring particularly to Fig. 1 it will be seen that the present embodiment of the invention comprises a chassis carrying a member pivotally mounted on the chassis for oscillation in a vertical plane. The pivot point is positioned in such a manner that the hips of the occupant (body pivot) will lie very close to and forward of the vehicle pivot point.

Although I have shown a vehicle having three wheels it is to be understood that the number of wheels is not controlling and that the principles of this invention may be applied to similar vehicles having a greater number of wheels or having three wheels arranged with a single driving wheel at the rear and a pair of steering wheels 15 at the front thereof.

It will be seen that the driving mechanism of my invention comprises an oscillating member 10 having a saddle 11 at the rear thereof and a hand grip 12 at its forward portion. The member 10 is mounted on a chassis 13 by means of a pivot 14 positioned under the rear portion of the seat 11. It should be noted that the position of the pivot 14 corresponds rather accurately to the position of the hip of an operator seated upon the vehicle. The importance of this feature will appear as the discussion of the invention proceeds.

The oscillating member 10 carries an arcuate rack 15 adapted to mesh with driving gears on the axes of the driving wheels. In its preferred embodiment my invention contemplates two driving wheels at the rear of the chassis each of said wheels being mounted on independent parallel shafts suitably journaled in the chassis and carrying pinions 16 and 17. It will be noted that the pinions are operatively connected to the wheel shafts by overrunning clutches comprising sleeves 18 and 19 which insure positive forward drive of one shaft no matter what the direction of rotation of the meshing pinions, while the other shaft rotates freely within its clutch. The 40 arcuate rack 15 meshes with the forward pinion 16 which is positively driven thereby and in turn drives the rear pinion 17.

The operator sits upon the saddle 11 and rests his feet upon the steering bar 25 mounted on the frame which carries axle 20 of the forward steering wheel 21 and grasps the hand grip 12 with his hands. In order to cause motion of the vehicle the operator alternately presses down on the hand grip and pulls up on the hand grip thereby causing the member 10 to oscillate about the pivot point 14. It will be seen that in downward motion the large muscles of the abdomen, the muscles of the legs and the muscles of the arms and shoulders all cooperate with the force of gravity acting on the body of the operator to apply a relatively great force to the hand grip. In upward motion the muscles of the legs, shoulders and arms cooperate with the large muscles of the back to give 60

a substantially equal force applied for driving. This effect cannot be obtained unless the pivot point of the device is positioned under or to the rear of the saddle while markedly good effects 5 are obtained with a pivot point placed not substantially forward of that point in the saddle where the hip bones contact the saddle. Best results are achieved with a pivot placed approximately at the rear of the saddle.

10 As noted above positioning of the pivot point is a highly important feature in designing an occupant-driven vehicle of the present type for maximum speed. It is important, however, that careful attention be given to the matter of transmitting the power to the driving wheels. Cranks and the like have points in the rotation of the crank at which the power supplied has only a very low component of force available for forward driving. In large engines the effect of this 15 feature can be largely overcome by the use of a fly wheel but in a child's toy vehicle I have found that the use of cranks is objectionable in that it does not permit application of the maximum force to the driving wheels.

20 25 The drive mechanism shown here has been found to be peculiarly adapted to use in an occupant-propelled vehicle having a pivot point positioned in the manner noted above. Each of the pinions 16 and 17 is securely affixed to one 30 of the sleeves 18 and 19, about the corresponding axle 22. A pin 23 through the axle 22 is adapted to engage notches in the end of the sleeve which is urged toward the pin by a spring 24 on the opposite side of the pinion.

35 40 The rack and pinion type of drive and more particularly the arcuate rack shown here are admirably adapted to the present purpose. By using a double rack operating on two pinions each of which is connected to the driving shaft by a suitable type of overrunning clutch I may avoid the use of a double axle if desired. It is to be understood that with a double rack operating 45 on two pinions the teeth of the two members of the rack must mesh with the pinions on opposite sides of the shaft. Alternatively, the invention contemplates the use of a single rear driving wheel with a pinion on each side thereof and an arcuate rack on one side meshing with the forward side of one pinion and an arcuate rack 50 on the other side meshing with the rearward side of the other pinion. It will be apparent that the device may be modified in a large number of different ways by using mechanical expedients known to the prior art in place of the novel drive here shown. But in any event it is preferred 55 that the transmission shall be so designed that positive drive will be given to the wheels whenever the oscillating member 10 is moved either up or down. It is also desirable that the device 60 shall be adapted to "coast" in such a manner that oscillating member 10 will not be caused to operate by rotation of the driving wheels.

Various other attachments may be added to the vehicle such as lights or suitable brakes and 65 it is to be understood that such modification is contemplated by the present invention.

I claim:

1. In an occupant propelled vehicle having a chassis and a forward wheel-carrying steering 70 axle pivotally connected to said chassis for transverse rotation with respect thereto and a rear

wheel-carrying driving axle mounted on said chassis; an occupant supporting member mounted for oscillation in a vertical plane about a pivot near the rear of said chassis, a hand grip on the forward end of said oscillating member, a saddle 5 on the rear of said member adjacent to and forward of said pivot, and means operatively connecting said oscillating member and said driving axle to cause rotation of said driving axle upon movement of said oscillating member. 10

2. In an occupant propelled vehicle having a chassis, a wheel-carrying steering axle adapted to be operated by the feet on the forward end of said chassis, a pair of driving axles on the rear end of said chassis, a wheel on one end of one 15 of said driving axles, a wheel on the opposite end of the other of said driving axles, a pinion carried by a sleeve about each of said axles, said pinions being in mesh with each other, a pin through each of said axles adjacent one end of 20 said sleeves, a spring mounted about each of said axles to force said sleeves toward said pins, notches in the end of each of said sleeves adjacent each of said pins shaped to catch said pin and drive said axle upon rotation of the pinion in 25 a direction to drive said axle for forward motion and to overrun said pin upon rotation of the pinion in the opposite direction, a member mounted on said chassis for oscillation in a vertical plane about a pivot, a hand grip on the 30 forward end of said member and a saddle on the rearward end of said member, said saddle being adjacent and forward of said pivot, and an arcuate rack on a rearward extension of said member, said rack being meshed with the pinion on 35 the foremost of said driving axles.

3. In an occupant propelled vehicle having a chassis, a wheel-carrying steering axle on the forward end of said chassis adapted to be operated by the feet, a pair of driving axles on the 40 rear end of said chassis, a wheel on one end of one of said driving axles, a wheel on the opposite end of the other of said driving axles, a pinion mounted about each of said axles and operatively connected thereto by an overrunning clutch 45 adapted to cause positive forward drive of each of said axles by the said pinion and permit free rotation of said pinions in a reverse direction, said pinions being in mesh with each other, a member mounted on said chassis for oscillation in a vertical plane about a pivot, a hand grip on the forward end of said member and a saddle on the rearward end of said member, said saddle being adjacent and forward of said pivot, and an arcuate rack on a rearward extension of said member, said rack being meshed with the pinion on 50 the foremost of said driving axles.

4. In an occupant propelled vehicle, two parallel rear driving axles in the same horizontal plane, each of which carries a driving wheel, said driving wheels being on opposite sides of the vehicle, a pinion operatively connected to each of said driving axles by an overrunning clutch, said pinions being meshed, and means to impart reciprocating rotary motion to the pinion on the 65 foremost of said axles, said overrunning clutches being adapted to transmit rotary motion to said driving axles in a direction to cause forward motion of the vehicle and to rotate freely about said axles in the opposite direction. 70

EARNIE W. LUCAS.
